WORK SUPPORT

Ralph E. Gordinier, Detroit, Mich., assignor to
Special Engineering Service, Incorporated, De-
troit, Mich., a corporation of Michigan

Application June 26, 1944, Serial No. 542,227

2 Claims. (Cl. 90—59)

1

This invention relates to a work support.

In the machining of long pieces which are mounted at each end, it is sometimes desirable to provide support between the ends to prevent distortion and vibration of the work as it is being machined. It is an object of the present invention to provide such a support in such a manner that the support cannot be forced downwardly by any vibration or pressure of the work. Other types of devices intended for this purpose have been found unsatisfactory because of the fact that they were responsive to vibration of machinery and would gradually give way under the vibratory action and pressure of the work.

In the drawings:

Fig. 1 illustrates a sectional view of the device shown in operation.

Fig. 2 is a horizontal section on lines 2—2 of Fig. 1.

Fig. 3 is a vertical section on line 3—3 of Fig. 1.

Fig. 4 is a view similar to Fig. 1 showing the support in retracted position.

In Fig. 1 a work piece is shown at W. This piece is being supported by the device to be described which consists of three main parts, a housing 10, a vertical plunger 11, and a horizontal plunger 12. The vertical plunger 11 is recessed as shown in Fig. 3 so that it is L-shaped. The cut-out portion receives the end of the member 12. A pin 14 in the side of plunger 11 is received in a slot 15 of the horizontal plunger 12. The horizontal or actuating plunger 12 has a hardened and ground surface 15a. This surface 15a is preferably ground at an angle of 10° to the horizontal; it may be from 7° to 14° and such angular surface 15a cooperates with a similar surface 16 on the vertical plunger 11. The slot 15 has the same angle in 12 as does the surface 15a.

The horizontal or actuating member 12 is operated by a shaft 20 which extends into the housing 10. This shaft has a rotating fit with member 12 at the point 21 but will exert lateral force on the plunger 12. The shaft is also slotted and grooved at points 22 and 23 to cooperate with a ball 24 so that it may be locked in position when retracted and turned as shown in Fig. 4. A round handle 25 is mounted on the end of the shaft for convenient operation. A spring 26 presses against a retaining collar 27 at one end and at the other end against the horizontal plunger 12.

In operation it will be seen that movement of the plunger 12 to the right will exert an upward force on member 11. Movement of the mem-

2

12 to the left by reason of the pin 14 will cause a positive downward movement of member 11. The angle of the surface 15a is such that no downward pressure on member 11 will cause movement of member 12 against the spring 26 which holds the member 12 to the right. Consequently, when a device is put in place under a work member, the shaft 20 is released from the position of Fig. 4 to a position in which the spring 10 urges member 12 to the right and forces member 11 upwardly against the work. Any vibration of the work might cause somewhat further movement to the right of member 12 and a slight increase in upward pressure of member 11. However, no vibratory forces or pressure from above will cause member 11 to move downwardly.

To insure the fixed position of the member 11 it is only necessary that the spring 26 be strong enough to just overcome the friction of the 20 operating sliding parts.

It will be seen that the action produced by the particular angle on the cam surfaces in cooperation with the light spring pressure gives the jack 25 the characteristic of following to the work piece through any motion that might be caused by vibration.

What I claim is:

1. A work support comprising a base, an actuating plunger slidable therein and spring biased in one direction by a relatively light spring, a jack plunger slidable in said base and cooperating inclined surfaces on said two plungers, said cooperating surfaces being at an angle of approximately 10° whereby the actuating plunger forms 30 a solid support for the jack plunger and whereby the spring pressure combined with the angle of said inclined surfaces prevents any reverse motion caused by downward pressure on the work end of the plunger, and a shaft having a swiveling coupling with the actuating plunger by which the said plunger may be withdrawn and the shaft turned to lock the shaft and plunger in withdrawn position by an interlock with the base.

2. A work support comprising a base, a horizontal plunger slidable therein and spring biased in one direction by a relatively light spring, a vertical plunger slidable in said base and cooperating cam surfaces on said two plungers, the angle of said cooperating cam surfaces being approximately 10° from the horizontal whereby the horizontal plunger forms a solid support for the vertical plunger and whereby the spring pressure combined with the angle of said cam surfaces prevents any reverse motion caused by downward pressure on the work end of the plunger, and means connecting the two plungers whereby 55

manual retraction of the horizontal plunger will cause positive lowering of the vertical plunger.
